UNITED STATES PATENT OFFICE.

ARTHUR T. KUEHNER, OF ELKRIDGE, MARYLAND.

LOCOMOTIVE DRIVING BOX.

1,425,492.

Specification of Letters Patent. Patented Aug. 8, 1922.

Application filed July 12, 1920. Serial No. 395,691.

To all whom it may concern:

Be it known that I, ARTHUR T. KUEHNER, a citizen of the United States, residing at Elkridge, in the county of Howard and State of Maryland, have invented certain new and useful Improvements in Locomotive Driving Boxes, of which the following is a specification.

This invention relates to an improved locomotive driving box of the general type disclosed in my copending application filed November 20, 1919, Serial No. 339,347 and has as one of its principal objects to provide a driving box wherein even though the wheel hub is jammed against the face plate employed, said plate may, nevertheless, be easily and quickly removed.

A further object of the invention is to provide a driving box wherein the face plate employed will be formed of sections and wherein said sections may be removed laterally.

And a still further object of the invention is to provide a driving box wherein the weight of the load will be employed for holding the face plate sections against upward movement but wherein even should the spring saddle resting upon the box break, the plate sections will, nevertheless, be firmly held in position.

Other and incidental objects will appear hereinafter.

In the drawings:

Figure 1 is a front elevation of my improved driving box,

Figure 2 is a side elevation of the box.

Figure 3 is a vertical sectional view taken medially through the box,

Figure 4 is a fragmentary top plan view particularly showing the locking lugs at the upper ends of the sections of the face plate employed,

Figure 5 is a perspective view showing one of the sections of the face plate in detail,

Figure 6 is a fragmentary vertical section taken on the line 6-6 of Figure 4.

In carrying the invention into effect, I employ a box body 10 provided at its inner side with vertical flanges 11 and at its outer side with vertical flanges 12, these flanges being adapted to cooperate for receiving a pedestal for the box. The box body is recessed in the usual manner to receive a drive axle and seated within the box body is a

crown brass 13 for journaling said axle. As particularly shown in Figure 3, this crown brass is provided at its outer end with an upstanding arcuate stop shoulder 14 seating in a suitable recess in the outer side of the box body for holding the crown brass against inward movement and projecting from the outer end of the brass beyond the box body is an arcuate flange 15 located at the inner margin of the brass. Depending from the legs of the box body at its inner side are lugs 16 and depending from the box body at its outer side are similar lugs 17 which overhang the outer side of the box body at their upper ends to provide stop shoulders 18. Fitting between the legs of the box at their lower end portions is a shelf 19 provided with lugs 20 mating with the lugs 16 and 17 respectively. Engaged through all of the lugs at the inner side of the box body is a bolt 21 and engaging through the respective pairs of lugs at the outer side of the box body are bolts 22. The shelf is thus rigidly secured between the legs of the box body and will serve to tie the lower end portions of the legs together and brace the legs with respect to each other. Rested upon the shelf is a grease cellar 23 removably secured between the lower end portions of the legs.

85

As will now be observed, the box body 10 is formed at its outer side with an upwardly sloping or beveled outer face and overlying the outer side of the box body is a face plate which, as particularly shown in Figure 2, is formed with a downwardly sloping or beveled inner face mating with the outer face of the box body. The flanges 12 are, of course, beveled at their outer sides to conform to the inclination of the outer face of the box body and the face plate is of a width to overlie these flanges mating therewith. The face plate is formed of companion semi-circular sections 24 meeting at their upper ends medially of the box body and upstanding from the upper ends of said sections are confronting lugs 25 through which is engaged a tie bolt 26 rigidly connecting the sections. The sections of the face plate are formed to fit the flange 15 of the crown brass and at their lower ends seat against the shoulders 18 of the lugs 17 of the box body, and depending from the sections at their lower ends are inwardly overhanging yokes 27, the inner ends of which

100

105

110

abut the outer sides of said lugs. As particularly shown in Figure 2, the lower end portions of the flanges 12 of the box body are, at their outer sides, provided with vertical notches 28 to accommodate the yokes and threaded into the lugs 17 or otherwise fixed thereto are laterally projecting posts 29 over which the yokes slidably fit. The posts will thus cooperate with the shoulders 18 for sustaining downward thrust upon the sections of the plate and will coact with the yokes 27 for securing the lower end portions of said sections against outward displacement away from the outer face of the box body. 10

Freely fitting through the box body adjacent its upper corners are bolts 30 provided at their outer ends with flat heads 31, the inner ends of which are, as shown in Figure 6, formed with oppositely beveled edges defining at the inner end of each bolt head reversely presented shoulders. The upper end portions of the sections of the face plate are formed with annular recesses 32 to freely receive the bolt heads and entering said recesses are slots 33 through which the bolt heads may be projected. Further, as also shown in Figure 6, the box body is provided at its outer side with recesses 34 into which the bolt heads may be retracted lying 20 flush with the outer face of the box body. Thus, by withdrawing the bolts so that the heads thereof are disposed within these recesses, the sections of the face plate may be secured against the outer side of the box body when the bolts may be projected to dispose the heads thereof within the recesses 32. Then, by rotating the bolts a half turn, the bolt heads will be disposed to coact with the bottom walls of the latter recesses so 30 that the nuts at the inner ends of the bolts may be tightened for rigidly securing the upper end portions of the sections against the box body. The reversely presented shoulders upon the inner ends of the bolt heads will coact with the bottom walls of the recesses 32 for holding the bolts against rotation so that the nuts of the bolts may be readily tightened or loosened.

Formed in the upper end of the box body near its inner side is a medially disposed recess 35 and formed in the upper end of the box body at its outer side is a similar recess 36 arranged opposite to the recess 35. The recess 36 opens through the outer side of the box body, being closed at its outer side by the sections of the face plate, and seating against the bottom wall of said recess to fit therein are mating rearwardly projecting lugs 37 formed on the upper end portions 50 of the sections of the face plate at their meeting ends. The recess 35 is designed to receive one leg 38 of a spring saddle while the recess 36 is designed to receive the other leg 39 of said saddle. The legs of the spring saddle have been conventionally shown.

Thus, as will be perceived, the leg 39 of the spring saddle will rest against the lugs 37 of the face plate so that the weight of the load will be utilized for maintaining these lugs seated against the bottom wall of the recess and consequently holding the sections of the face plate against upward movement. Formed on the outer margin of the box body at its upper end are inwardly beveled shoulders 40 lying at opposite sides of the recess 36 and extending across the upper ends of the flanges 12. Overlying these shoulders are rearwardly directed lugs 41 formed on the upper ends of the sections of the face plate above and beyond the flanges 37. The flanges 41 are, as particularly shown in Figures 2 and 3 of the drawings, provided with inwardly beveled lower faces mating with the shoulders 40 of the box body so that the flanges will thus coact with said shoulders and operate in conjunction with the bolts 30 for locking the upper end portions of the sections of the base plate against outward movement away from the box body. Since it sometimes happens that a spring saddle breaks, which would, in the practical use of the present box, result in relieving the flanges 37 of the weight of the load, stud bolts 42 are fitted freely through the flanges 41 and threaded into the box body for securing the sections of the face plate against upward movement so that even should the spring saddle break, upward thrust against the sections of the face plate could not serve to displace said sections. As will thus be seen, the face plate will be firmly and securely held to the box body and secured in a suitable dove-tailed channel in the outer faces of the sections of said plate are arcuate portions of a hub bearing 43, the portions of said bearing meeting at their upper ends and extending to the lower ends of the sections. As will be readily understood, this hub bearing is disposed to confront the hub of a drive wheel and may be renewed for taking up end play or for alining the wheels of a locomotive. In this connection, it is to be observed that since, as shall presently appear, the face plate may be readily removed from the box body, I provide an arrangement wherein, by properly varying the thickness of the bearing 43, all of the wheels of a locomotive may be easily and accurately alined.

Formed on the sections of the face plate 120 at their outer side edges are medially arranged apertured lugs 44 respectively designed to receive a suitable tool for removing said sections. To accomplish this result, the load is lifted from the spring saddle so 125 that the legs of said saddle may be lifted. The bolts 30 are then loosened and said bolts retracted in the manner previously indicated to dispose the heads 31 thereof within the recesses 34 of the box body. The stud bolts 130

42 are then removed and the tie bolt 26 displaced. As will be clear, the sections of the face plate may then be lifted, as shown in dotted lines in Figure 2, to raise the lugs 37 5 thereof out of the recess 36 and elevate the yokes 27 above the posts 29, it being observed that the notches 28 are of a height to permit the yokes to clear said posts. Consequently, a suitable tool may then be engaged in each 10 of the lugs 44 of the sections of the face plate and the sections removed laterally in opposite directions. Thus, as will be seen, the sections of the face plate may be readily displaced and by simply reversing the operation 15 just described, the sections of the face plate may, of course, be as easily again fitted in position. In this connection, attention is directed to the fact that since the box body and face plate are formed with reversely 20 beveled faces, it will be necessary to move the sections of the face plate upwardly but slightly before clearance will be had between the face plate and a confronting wheel hub. Thus, even though the wheel hub 25 should be jammed against the face plate, the sections of said plate may, nevertheless, be readily removed.

Having thus described the invention, what is claimed as new is:

- 30 1. A journal box including a box body, a crown brass fitted therein and provided at its outer end portion with a stop shoulder coacting with the box body for holding the brass against inward movement through the 35 box body and a face plate secured to the outer side of the box body and coacting with the brass for holding the brass against outward movement.
2. A journal box including a box body, 40 and a face plate secured to the outer side of the box body, the box body and face plate being formed with mating beveled side faces.
3. A journal box including a box body, a 45 crown brass fitting therein and provided with stop means coacting with the box body for holding the brass against inward movement through the box body, and a face plate secured to the outer side of the box body co- 50 acting with the brass for holding the brass against outward movement.
4. A journal box including a box body having a vertically inclined outer face, and a face plate secured to the outer side of the 55 box body and provided with a vertically inclined inner face seating against the outer face of the box body.
5. In a journal box, the combination of a box body, and a face plate secured to the 60 outer side of the box body and tapered in thickness.
6. In a journal box, the combination of a box body, a sectional face plate seating against the outer face of the box body, 65 means securing the lower end portions of the
- sections to the box body, and coacting means fixed upon the upper end portions of the sections and the box body respectively locking the sections against separation, the means upon the sections being disposed for engagement by a leg of a spring saddle holding the sections against upward movement. 70
7. In a journal box, the combination of a box body provided with side posts, a sectional face plate seating against the outer face of the box body, the sections of said plate being formed at their lower end portions with yokes straddling said posts, and coacting means fixed upon the upper end portions of the sections and the box body respectively locking the sections against separation, the means upon the sections being disposed for engagement by a leg of a spring saddle holding the sections against upward movement. 75
8. In a journal box, the combination of a box body, a sectional face plate seating against the outer face of the box body, and coacting means fixed upon the sections of said plate and the box body respectively locking the sections against separation, the means upon the sections being disposed for engagement by a leg of a spring saddle holding the sections against upward movement. 80
9. In a journal box, the combination of a box body provided at its upper end with a recess, a sectional face plate seating against the outer face of the box body, and lugs upon the plate sections received in said recess for engagement by a spring saddle 90 and coacting with the end walls of the recess for locking the sections against separation, the sections being initially shiftable upwardly to clear said lugs and being then separable for removal sidewise in opposite 100 directions.
10. In a journal box, the combination of a box body, a sectional face plate seating against the outer face of the body box, lugs upon the sections coacting with the box 110 body for locking the sections against separation, and other lugs upon the sections overhanging the box body coacting therewith securing the sections against outward movement away from the box body, the 115 sections being initially shiftable upwardly to clear all of said lugs and being then separable for removal sidewise in opposite directions.
11. In a journal box, the combination of a box body, a sectional face plate seating against the outer face of the box body, coacting means fixed upon the sections of said plate and the box body respectively securing the sections against separation, means 120 carried by the upper end portions of the sections to overhang the box body coacting therewith securing the sections against outward movement away from the box body, the sections being initially shiftable up- 125 130

wardly to clear all of said means and being then separable for removal sidewise in opposite directions, and means coacting between said second-mentioned means and the box body securing the plate sections against upward movement.

12. In a journal box, the combination of a box body, a sectional face plate seating against the outer face of the box body, lugs upon the sections coacting with the box body for locking the sections against separation, other lugs upon the sections overhanging the box body coacting therewith securing the sections against outward movement away from the box body, the sections being initially shiftable upwardly to clear all of said lugs and being then separable for removal sidewise in opposite directions, and bolts extending through the latter lugs co- 20 acting with the box body for securing the plate sections against upward movement.

13. A journal box including a box body, a face plate seating against the outer face of the box body, and bolts securing the plate to the box body and provided with heads having reversely presented shoulders to coact with the plate for holding the bolts against rotation, the bolts being rotatable

to a position whereby said bolts may be retracted to free the plate.

14. A journal box including a box body, a crown brass carried thereby and provided with stop means coacting with the box body for limiting the brass against inward movement, the brass projecting at the outer side of the box body, and a face plate at the outer side of the box body resting upon the projecting portion of the crown brass, the face plate being removable in a plane parallel to the adjacent face of the box body.

15. A journal box including a box body provided adjacent its outer side with pedestal flanges, a face plate detachably seating against the outer side of the box body and provided at its lower end with yokes overhanging the face plate at its inner side to coact with said flanges for limiting the plate against upward movement, and means coacting with said yokes locking the plate against outward movement away from the box body.

In testimony whereof I affix my signature.

ARTHUR T. KUEHNER. [L. s.]
